UNITED STATES PATENT OFFICE.

JAKE MANFRED STIVERS, OF SPRINGFIELD, MISSOURI, ASSIGNOR TO NATIONAL
QUICK PATCH COMPANY, OF SPRINGFIELD, MISSOURI, A CORPORATION OF
MISSOURI.

PROCESS FOR REPAIRING BILLIARD-CLOTH.

1,097,481.

Specification of Letters Patent.

Patented May 19, 1914.

No Drawing.

Application filed August 8, 1913. Serial No. 783,710.

To all whom it may concern:

Be it known that I, JAKE M. STIVERS, a citizen of the United States, residing at Springfield, Greene county, Missouri, have 5 invented a certain new and useful Improvement in Processes for Repairing Billiard-Cloth, of which the following is a full, clear, and exact description, such as will enable others skilled in the art to which it appertains to make and use the same.

This invention relates to a process for repairing damaged billiard cloth.

The main object of my invention is to provide means for enabling billiard cloth to 15 be repaired in such a manner that the repaired place in the cloth will be practically invisible and will have substantially the same texture or wearing surface as the balance of the cloth.

20 In repairing a hole in billiard cloth according to my process, I first fill the hole with my improved repairing composition which I will hereafter describe. The composition is in a plastic or semi-plastic condition when it is applied so that it can be forced or beaten into the hole and smoothed out so as to form a patch of the same thickness as the cloth, that merges into the cloth at the edge of the hole. It will, of course, 25 be understood that the billiard cloth being repaired is in operative position on a billiard-table or other hard flat supporting surface so that when the patching composition is forced into the hole in the cloth it will adhere to the flat supporting surface which the cloth covers after said composition has set or become solid. After the patching composition has been smoothed out 30 so as to fill the hole evenly, an adhesive of

35 some suitable character is spread over the composition and thereafter powdered billiard cloth of the same color as the cloth being repaired is sprinkled over the composition so as to form a top coating for same, 40 thus forming a patch that is practically invisible and which has substantially the same texture or wearing surface as the balance of the cloth.

I prefer to form the patching composition 45 from rubber, gum, cloth nap, and plaster Paris, and I have found in practice that a composition composed of the following ingredients mixed in approximately the proportions specified forms an efficient substance for patching billiard cloth: approxi-

mately 2% of rubber; approximately 2% of gum; approximately $\frac{1}{2}\%$ of cloth nap; approximately 4% of plaster Paris. The rubber that I prefer to use is in a liquid state or condition when it is mixed with the other 50 ingredients, and the gum that I prefer to use is liquid gum which is in a liquid state at the time the ingredients are mixed together. Glue or any other suitable adhesive may be spread over the patching composition prior to sprinkling the powdered billiard cloth over the composition so as to 55 form a top coating for same.

A composition of the character described and the process of using it, enables a hole 70 or damaged place in billiard cloth to be repaired so effectively that the patch is invisible, it is solid, it is durable, and the repaired surface is of the same color and texture as the remainder of the cloth and is 75 free from ridges, bumps or seams. If the billiard cloth is merely torn or slit, I first cut the cloth away from around the tear so as to completely remove the cloth and thus form a hole in the cloth, and thereafter I fill the hole with my improved composition and apply a top coating to same 80 in the manner previously described.

Having thus described my invention, what I claim as new and desire to secure by Letters Patent is:

1. A process for repairing a hole in billiard cloth, which consists in filling the hole with a plastic or semi-plastic substance of suitable character that will set and smoothing it out so as to completely fill the hole and thus form a patch of the same thickness as the cloth, and imparting to the patch the same color as the cloth.

2. A process for repairing a hole in billiard cloth, which consists in filling the hole with a plastic or semi-plastic substance of suitable character that will set and smoothing it out so as to completely fill the hole and thus form a patch of the same thickness as the cloth, and thereafter applying powdered billiard cloth to said patch so as to form a top coating on same of the same color as the billiard cloth being repaired.

3. A process for repairing a hole in billiard cloth, which consists in filling the hole with a plastic or semi-plastic substance of suitable character that will set and smoothing it out so as to completely fill the hole and thus form a patch of the same thickness 110

as the cloth, applying an adhesive to said patch, and thereafter sprinkling powdered billiard cloth over said adhesive so as to impart to the patch the same color and 5 character of surface as the cloth being repaired.

4. A process for repairing the cloth top surface of a billiard-table, which consists in cutting the cloth away from around the 10 damaged or defective portion so as to form a hole in the cloth, filling the hole evenly with a suitable composition that will be solid and durable after it has set, and thereafter coating the top of said composition 15 with powdered cloth of the same color as the cloth being repaired.

5. A process for repairing the cloth top surface of a billiard-table, which consists

in cutting the cloth away from around the damaged or defective portion so as to form 20 a hole in the cloth, filling the hole evenly with a composition composed of rubber, gum, cloth nap, and plaster Paris so as to form a patch of the same thickness as the cloth, applying an adhesive to said patch, 25 and thereafter sprinkling powdered billiard-cloth over said adhesive so as to form an invisible patch.

In testimony whereof I hereunto affix my signature in the presence of two witnesses, 30 this 5th day of August 1913.

JAKE MANFRED STIVERS.
